CLAIM

The ornamental design of a golf club shaft, as shown and described.

DESCRIPTION

FIG. 1 is an enlarged fragmentary view of a portion of the golf club shaft showing my new design;

FIG. 2 is an end view as seen from the smaller end of the shaft;

FIG. 3 is a perspective view of the shaft.

The characteristic feature of my design resides in the repetitive stepped pattern of long, medium, short and then short, medium, long steps along the shaft.
